(No Model.)

W. CRADDOCK.

FIRE ESCAPE.

No. 309,031. *Fig. 1*

Patented Dec. 9, 1884.

UNITED STATES PATENT OFFICE.

WILLIAM CRADDOCK, OF NEW YORK, N. Y.

FIRE-ESCAPE.

SPECIFICATION forming part of Letters Patent No. 309,031, dated December 9, 1884.

Application filed July 12, 1884. (No model.)

To all whom it may concern:

Be it known that I, WILLIAM CRADDOCK, of the city, county, and State of New York, have invented a new and useful Improvement 5 in Fire-Escapes, of which the following is a full, clear, and exact description.

Reference is to be had to the accompanying drawings, forming part of this specification, in which similar letters of reference indicate corresponding parts in both the figures.

Figure 1 is a front elevation of my improvement, the vault being shown in section. Fig. 2 is a sectional side elevation of the same.

The object of this invention is to facilitate 15 the escape of people from burning buildings when the ordinary passage-ways have become impassable.

The invention consists in a fire-escape constructed with a carriage moving up and down 20 upon guide-ropes attached at their upper ends to bars secured to the building, and at their lower ends to a bar or plate secured in a vault beneath the sidewalk.

To the top and bottom of the carriage are attached the ends of a rope, which passes around 25 guide-pulleys placed at the upper part of the building and in the lower part of the sidewalk-vault, and around a drum placed in the said vault, the said rope being provided with a weight, whereby the empty carriage will be raised by the said weight, and the loaded carriage will be lowered by the weight of its load. To the drum around which the hoisting-rope passes is attached a large wheel, upon the face 35 of which rests a brake-shoe swiveled to a screw passing through a stationary nut, and provided with a key whereby the ascent and descent of the carriage can be readily controlled. At the opposite sides of the drum are placed vertical 40 rollers, to prevent the parts of the hoisting-rope passing to and from the said drum from rubbing against each other, as will be herein-after fully described.

A represents the carriage, which may be 45 made of any desired or convenient size or style, and which moves up and down upon wire ropes or chains B. The upper ends of the guide-ropes B are attached to the ends of a cross-bar, C, which is secured to the outer ends of bars 50 D. The bars D pass in through the wall or cornice of the building, and are designed to be firmly secured to the frame of the said build-

ing. The guide-ropes B pass down through an opening, E, in the sidewalk F, and their lower ends are connected, by eyebolts G or other 55 suitable means, to bars or plates H, placed in the lower parts of a vault, I, formed beneath the sidewalk F, and secured to the walls of the said vault or other convenient support. The opening E is designed to be made of such a 60 size that the carriage A can pass through it readily, and is closed when the fire-escape is not in use by a gate, J, which is made in two parts hinged at their outer edges, so that they can be opened and closed without interfering 65 with the guide-ropes B.

To the top of the carriage A is secured the end of a wire rope or chain, K, which passes over a guide-pulley, L, pivoted to the center of the cross-bar C, passes along the upper 70 part of the building and over a pulley, M, pivoted to the center of a cross-bar, N, which is bolted at its ends to the outer ends of two bars, O. The bars O pass in through the wall or cornice of the building, and are securely 75 bolted to the frame of the said building. From the pulley M the rope or chain K passes down along the side of the building, passes through an opening, P, in the sidewalk F, passes around a pulley, Q, pivoted to a bracket or 80 other support attached to the bar or plate H, and passes thence to and around a drum, R, journaled to supports formed in or secured to the walls of the vault I. From the drum R the rope K passes to and around a pulley, S, 85 pivoted to a bracket or other support attached to the bar or plate H, and passes up and is attached to the bottom of the carriage A, the point of attachment and the position of the pulley S being so arranged that the rope K will pass 90 the guide-rope B without touching it.

To the rope K, between the pulley M and the sidewalk F, is attached a weight, T, in such a position as to be up when the carriage A is down and down when the carriage is up, 95 and of such a gravity as to overbalance and raise the carriage A when empty.

To the drum R is attached a large wheel, U, upon the face of which rests the brake-shoe V.

To the brake-shoe V is swiveled a screw, W, 100 which passes through a nut, X, secured in an aperture in the sidewalk F. The upper end of the swiveled screw W is squared to fit into the socket of a key, Y, so that by turning the

said key the brake-shoe V can be forced down upon the wheel U with any desired force, and the descent of the carriage can be readily controlled by a person upon the sidewalk. The 5 key Y, when not required for use, can be locked to a staple or other support attached to the side of the building or the wall of the vault I, near the opening E. When the key Y is detached, the key-hole in the sidewalk is closed 10 with a cover, Z, to prevent the screw W from becoming clogged with dirt. Upon the opposite sides of the drum R are placed two vertical rollers, 1, the lower ends of which are pivoted to the bar or plate H, and their upper 15 ends are pivoted to a support in the upper part of the vault I. The rollers 1 are so placed as to prevent the parts of the hoisting-rope K that pass to and from the drum from rubbing against each other.

20 In using the fire-escape a person upon the sidewalk, having control of the key Y, applies the said key to the screw W and loosens the brake-shoe V, which allows the weight T to raise the carriage. When the carriage has been 25 raised to the desired height, the brake-shoe V is again tightened to hold the carriage in place while being loaded. When the carriage is loaded, the brake-shoe is loosened sufficiently to allow the carriage to descend with the desired 30 rapidity. In the same manner the carriage can be sent up and down until all the occupants of the building have been lowered.

Having thus described my invention, what I claim as new, and desire to secure by Letters 35 Patent, is—

1. In a fire-escape, the combination, with the guide-ropes B, arranged at the side of a building, of the carriage A, the rope K, having its ends attached to the top and bottom of the car and passing around guide-pulleys, and 40 a drum arranged below the sidewalk, the weight T on said rope, and a brake mechanism for said drum, substantially as herein shown and described.

2. In a fire-escape, the combination, with 45 the top supporting-bars, C'D, the bottom plate, H, and the guide-ropes B, of the car A, the pulleys L M Q S, the rope K, the drum R, the wheel U, and the brake, substantially as herein shown and described.

3. In a fire-escape, the combination, with the drum R and the rope K, of the wheel U, the brake-shoe V, the swiveled screw W, and its nut X and key Y, substantially as herein shown and described, whereby the ascent and 55 descent of the carriage can be readily controlled, as set forth.

4. In a fire-escape, the combination, with the rope K and the drum R, of the two vertical rollers 1, substantially as herein shown 60 and described, whereby the parts of the said rope passing to and from the said drum will be kept from contact, as set forth.

WILLIAM CRADDOCK.
